DESIGN FOR AN ICE WATER PITCHER

Clarence M. Burroughs, Glendale, Calif.

Application March 1, 1948, Serial No. 144,860

Term of patent 14 years

(Cl. D44—21)

To all whom it may concern:

Be it known that I, Clarence M. Burroughs, a citizen of the United States, residing at Glendale, in the county of Los Angeles and State of California, have invented a new, original, and ornamental Design for an Ice Water Pitcher, of which the following is a specification, reference being had to the accompanying drawing, forming part thereof.

Fig. 1 is a side elevational view of an ice water pitcher, showing my new design;

Fig. 2 is a top plan view;

Fig. 3 is an end view taken from the spout side; and

Fig. 4 is another end view thereof taken from the handle side.

I claim:

The ornamental design for an ice water pitcher, as shown.

CLARENCE M. BURROUGHS.
